ELECTROMAGNETIC VIBRATORY MOTOR

Edward L. Barrett, La Grange, Ill., assignor to
 Utah Radio Products Company, Chicago, Ill.,
 a corporation of Illinois

Application June 25, 1934, Serial No. 732,234

7 Claims. (CL. 200—90)

The invention relates generally to electromagnetic vibratory motors and more particularly has reference to a device which is especially well adapted for use in connection with systems for converting direct current of low potential into direct current of high potential, such, for example, as "B" battery eliminator systems which are primarily intended for use in automobile installations of radio receiving sets.

Heretofore in vibratory motors intended for this type of work, unusual difficulty has been encountered in obtaining a proper adjustment of the co-operating parts and especially of the several separable contacts. In manufacturing such devices, it has been necessary to adjust the parts by hand several times during assembly, which, since the clearances involved are measured in a few thousandths of an inch, requires considerable time and skill on the part of the workman, thus materially increasing the cost. Moreover, it has been found that in operation the vibratory contact member or reed of previous devices has a tendency to shift out of its original assembled position, thus disturbing the accurate adjustments and resulting in the failure of the device.

It has been customary to support the vibratory reed by a frame through the medium of what is known as a "stack" and which consists of a large number of layers of thin pieces of insulation and interposed strips of metal for contact purposes. I have discovered that the primary source of trouble in previous devices is the stack. Thus, if the elements of the stack are slightly loose when assembled, the constant vibration of the reed in operation will in time cause the reed to shift its position and even the slightest shift may disturb the adjustments to such an extent that the device becomes inoperative. Or, if the elements of the stack are slightly warped, uneven in thickness, or otherwise irregular, the parts cannot be assembled with any assurance that the operation thereof will be satisfactory for the expected life of the device nor with any degree of uniformity. Obviously if the devices are not alike after assembly, each device must be separately adjusted at an increased expense. These same disadvantages are present when the contacts with which the vibratory reed cooperates are supported from the stack with the increased possibility of some part shifting to destroy the adjustment.

An object of the present invention is to provide an electromagnetic vibratory motor which is simple in construction, in which the component elements may be assembled with such accuracy as to require only a final adjustment, and in which

the number of parts and the overall dimensions of the device are reduced to a minimum.

Another object of the invention is to provide a device of this character which includes a supporting frame and a vibratory element which are directly connected together without the use of any intermediate part whatsoever.

More specifically stated, another object of the invention resides in the provision of a vibratory motor which embodies a single member bent to form a frame structure having opposed parts upon which stationary contacts are fixedly mounted and between the ends of which a vibratory member is directly secured in such manner that the relationship of the vibratory reed to the assembly and to the fixed contacts is unvariable after assembly whereby contacts which are carried by the vibratory member may be permanently adjusted with respect to the fixed contacts as the final step of assembling the device.

Other objects and advantages will become apparent in the following description and from the accompanying drawing, in which:

Figure 1 is a longitudinal central section through a device embodying the features of the present invention.

Fig. 2 is a similar sectional view taken at right angles to the section shown in Fig. 1.

Fig. 3 is a greatly enlarged fragmentary sectional view showing the details of the mounting of the vibratory member and the several contacts, and is taken along the line 3—3 of Fig. 2.

Fig. 4 is a similarly enlarged transverse section through the device taken along the line 4—4 of Fig. 2 and looking in the direction of the arrows.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The vibratory motor, which has been shown in the drawing as illustrative of a device embodying the present invention, is of the type especially adapted for use in a system wherein direct current is mechanically interrupted to produce a transformed alternating current of higher potential which is then mechanically rectified to produce a direct current of high potential. With only minor changes, the present device can be used as

well in systems wherein the alternating current of high potential is rectified by means of a valve.

Referring to the drawing, 10 designates generally an electromagnetic vibratory motor which is housed within an enclosing container 11. The motor 10 embodies a frame 12, which, while it may be formed of several pieces, is preferably fashioned from an elongated strip of relatively heavy metal stock which if desired, may be of magnetically permeable metal, such as steel. Said strip is bent into an elongated, generally rectangular, or box-like structure having side walls 13, a closed end 14, and a split base 15 where the opposite ends of the strip are brought together. The extreme ends 16 of the strip are turned outwardly, as shown, to provide opposed meeting faces 17 of substantial size located approximately on the central longitudinal plane of the frame. In so far as it is possible, the meeting surfaces 17 are perfectly flat and parallel to said central plane of the frame.

The closed end 14 of the frame carries a small electromagnetic winding 18 which is permanently affixed thereto in any suitable manner at one side of the longitudinal plane on which the flat surfaces 17 are located. A preferred and simplified means for mounting the electromagnet on the frame is best seen in Fig. 2. The winding 18 is of the spool type and encircles a core 19 formed of a thin rectangularly shaped piece of magnetic iron. The winding 18 is supported upon a spool element 20 which fits closely about the core with the ends of the spool resting in recesses formed in the core. The margins of the core adjacent to said recesses are upset, as indicated at 21, to secure the core and winding permanently together. One end of the core, indicated at 22, is extended beyond the adjacent face of the spool element and is arranged to be received snugly in an appropriately dimensioned slot 23 formed in the closed end 14 of the frame. The core end 22 is preferably of reduced width to provide shoulders 24 for determining the proper position of the core and winding relative to the frame end. The electromagnetic winding structure may be secured to the frame in any suitable manner as by upsetting portions of the core end 22 or by soldering the parts together.

A vibratory member 25 in the form of an elongated reed of spring steel is mounted on the frame by interposing one end 26 thereof directly between the ends 16 of the frame and in abutting engagement with both of the plane surfaces 17. Preferably, as shown in Fig. 2, the frame surfaces 17 have both faces thereof knurled or otherwise provided with a plurality of crisscross lines to produce perfectly plane surfaces. Screws 27 or the like secure the frame ends 16 and the reed end 26 rigidly together. Washers 28 may be used to insure tightness and, since the parts are electrically connected, a contact 29 may be interposed between one of the washers and the adjacent frame end.

Thus, the reed may be permanently and securely mounted on the frame. The frame end 16, by an ordinary stamping process, can be so fashioned that the surfaces 17 thereon are perfectly plane within very close limits of tolerance. The reed end 26, being practically a plane surface, will fit accurately between the surfaces 17 and the assembly is completed by merely seating the screws 27 tightly. Hence no errors or inaccuracies of part relationships are introduced in the present assembly as is too frequently the case

when the reed is supported from the frame members by an interposed stack of laminations.

When the reed is assembled, it will extend between the frame sides 13 substantially on a parallel medial plane and the reed is so dimensioned as to reach nearly to the adjacent exposed face of the electromagnet core 19. This end of the reed carries a small armature 30 and it is preferred that the reed contacting face of the armature be knurled as in the case of the surfaces 17 to avoid reed distortion. Since the electromagnet is located at one side of the center plane, the armature by this construction is located at one side or eccentrically of the center of magnetic force exerted by the electromagnet. Where the frame 12 is fashioned of magnetically nonpermeable metal, the effective magnetic force results from magnetic flux leakage around the electromagnet. If the frame is of steel a substantially closed magnetic path is provided which includes the electromagnet core, the frame, and the reed. However, due to the reluctance of the thin reed, the flux leakage is still effective as a force to which the armature reed responds. Consequently, either magnetically permeable or nonpermeable metal may be used in the frame without materially affecting the efficiency of the device.

The frame sides 13 carry fixed contacts generally designated at 31 and these contacts are preferably located about half way along the free portion of the reed. Since the illustrated device is primarily intended to be used in a system wherein alternating current rectification is accomplished mechanically, four contacts are employed, two of which serve to effect an alternate interruption of a direct current circuit to the primary winding of a transformer, while the other two contacts alternately establish a rectifying connection between the transformer secondary and load. The contacts are mounted in transversely alined pairs on the frame sides 13 and, since the manner of mounting the contacts is the same, only one need be described.

Each contact comprises an elongated stud 32 having a head 33 which is faced with a layer 34 of a suitable contact material. The stud and head are preferably formed of a relatively soft current conducting material. The stud 32 extends through an insulation bushing 35 which is snugly seated in an aperture 36 formed in the frame side 13, the head 33 and contact 34 being located on the inner side of the frame. Mounted on the stud 32 next to the head 33 is a washer 37 of substantially greater diameter than that of the aperture 36 and between the washer and the frame side 13 is a still larger washer 38 of suitable insulation such as mica. Similarly, on the outer side of the frame is an insulation washer 39 and a smaller washer 40 having a lateral extension 41 for connection with a lead 42. The parts preferably are secured in place by upsetting the outer end of the stud 32 as indicated at 43. The larger dimensions of the washers 37, 38, 39 and 40 are important in order that the contact will be permanently and immovably secured to the frame. Where the contacts are mounted in pairs on the frame sides 13, the washers 38 and 39 may be common to both contacts (see Fig. 4).

The vibratory reed 25 carries contacts 44 which cooperate with the contacts 31 and to distinguish therebetween the contacts 31 and 44 will herein-after be respectively termed "fixed" and "movable" contacts. The movable contacts 44 are located on both sides of the reed and include spring arms 45 which, as shown in Figs. 2 and 3, extend

in outwardly offset pairs from common bases 46 which in turn are secured as by rivets 47 to the vibratory reed 25. Preferably the reed contacting faces of the bases are also knurled to avoid distortion of the reed. The point of connection between the bases 46 and the reed is between the fixed contacts and the fixed end of the reed, and the contact arms 45 extend in overlying relation to the contact faces 34 where the contact fingers 10 carry contacts 48 for cooperation with the fixed contact faces 34.

In operation, as the reed 25 vibrates, the pairs of contacts thereon will be moved into alternate engagement with the fixed contacts on the opposite frame sides.

The present construction has greatly simplified the assembly and adjustment of the parts. Thus, in assembly the fixed contacts 31 are preferably mounted on the frame before the vibratory 20 reed is assembled thereon. The frame with the fixed contacts properly secured thereto may be placed in a suitable jig or fixture wherein the proper spacing of the opposed fixed contacts can be effected by bending or offsetting the frame 25 sides, as shown in Fig. 1. Likewise the movable contacts 44 may be affixed to the reed before the reed is mounted on the frame and the reed may then be placed in a suitable jig or fixture for adjustment of the spacing of the movable contacts, 30 this adjustment being obtained by bending the fingers 45. The separately adjusted reed and frame are then assembled and it has frequently been found on final check that the unit requires no further adjustment. At worst, only a minute 35 adjustment is all that is ever necessary.

Thus the disadvantages resulting from inaccuracies in a frame, reed and stack construction or from differences in the thickness of the stack, or from the insecurity of the reed due to looseness 40 in the stack, all or any of which will impair or destroy the accuracy of adjustment, are entirely eliminated in the present construction.

The inherent disadvantages resulting from the vibrations of a motor of this character are minimized in the present instance by a special form 45 of enclosing casing. The motor, as shown in Figs. 1 and 2, is mounted in a container having an outer closed case comprising a can-like metal shell 49 and a tightly fitting cover 50 which are 50 permanently secured together in any suitable manner, as by spots of solder 51. The end or base of the cover is centrally apertured and is closed by an insulation plate 52 to which a plurality of projecting prongs 53 are secured. The 55 inner surface of the shell 49 is lined throughout with a layer 54 of felt or similar noise and vibration absorbing material, while an enlarged plug 55 preferably fashioned of sponge rubber is seated in the cover and within the open end of the case. The leads to the motor extend through passageways in the plug 55 for electrical connection with the several prongs.

The plug 55 within the shell is peripherally recessed, as at 56, and an inner metal shell 57 is 60 seated upon the reduced diameter portion thereof. A layer 58 of felt or the like lines the interior of the second shell 57. Preferably, the nested shells are spaced apart to allow the inner shell to move freely and to provide a dead air space 65 between the two shells. This structure serves with exceeding efficiency to absorb and deaden all noise incident to the vibration of the motor and effectively prevents transmission of vibrations to the exterior of the casing. Obviously, vibrations 70 cannot be transmitted to the prongs 53 and hence

the connection between the prongs and a complementary socket cannot work loose during the operation of the device. It is to be noted that the inner shell 57 is ungrounded whereby electrical interference due to sparking between the points 5 is effectively reduced.

From the foregoing, it will be evident that a novel vibratory motor structure has been provided which is exceedingly simple, may be assembled and adjusted efficiently and accurately, and is 10 noise and vibration proof. The simplified construction is sturdy. The necessary adjustments may be speedily obtained with an unusual degree of uniformity and such adjustments are permanent. The present device embodies few parts 15 which are so related that an unusually small and compact unit may be produced. In Figs. 1 and 2 the dimensions shown are substantially full scale.

I claim as my invention:

1. A vibratory motor comprising, in combination, a rigid frame divided to provide opposed flat faces located substantially on a central longitudinal plane of the frame, a vibratory member interposed and clamped directly between said 25 faces in abutment with both, means for rigidly securing the parts in such relationship, and means for effecting vibration of said member.

2. In a vibratory motor, the combination of a frame having opposed parts adapted to be 30 brought close together, and a vibratory reed rigidly secured in directly interposed relation between said parts and in contact therewith.

3. In a vibratory motor, the combination of a frame formed of a continuous piece of material 35 bent into box-like shape and having the opposite ends thereof turned to provide opposed faces of substantial size, and a vibratory reed having a portion thereof clamped between said faces and in direct face-to-face contact therewith, and with 40 the remainder of the reed projecting away from said faces for free vibration unobstructed by said frame.

4. In a vibratory motor, the combination of a frame formed of a continuous piece of material 45 bent into box-like shape and having the opposite ends thereof turned inwardly to provide opposed faces of substantial size adapted to meet substantially on a central longitudinal plane of said frame, and a vibratory reed secured between said 50 faces in direct face-to-face contact therewith to extend inside said frame substantially on said central plane.

5. In a vibratory motor, the combination of a frame formed of a continuous piece of material 55 bent into an elongated rectangular frame and having the opposite ends thereof turned to provide opposed faces, an electromagnet mounted at the closed end of the frame, and a vibratory reed secured between said faces in direct face-to-face 60 contact therewith and extending to a position for cooperation with said electromagnet.

6. A vibratory motor comprising, in combination, a closed frame divided to provide opposed flat faces located substantially on a central longitudinal plane of the frame, a vibratory reed interposed directly between said faces in abutment with both, means for rigidly securing the parts in such relationship, means for effecting vibration of said reed, fixed contacts rigidly mounted 70 on said frame, and cooperating contacts flexibly connected with said reed.

7. A vibrator for use in a B-battery eliminator for an automobile radio receiver or the like comprising, in combination, a rigid and generally 75

elongated frame presenting a laterally disposed face adjacent one end thereof, a cantilever type vibratory reed adapted to vibrate at a substantially fixed frequency determined largely by the resilient characteristics of the reed, said reed being fashioned in the form of an elongated flat strip of metal, means for clamping the butt end

portion of said reed in direct face-to-face contact with said face on said frame and with the remainder of the reed projecting toward the other end of said frame, and a plurality of make and break contacts arranged to be actuated by said reed in the vibration thereof.

EDWARD L. BARRETT.
